UNITED STATES PATENT OFFICE.

WILLIAM ARTHUR RAMSAY, OF HONOLULU, TERRITORY OF HAWAII.

ROTARY CANE-CUTTER.

1,209,618.

Specification of Letters Patent Patented Dec. 19, 1916.

Application filed June 8, 1916. Serial No. 102,555.

To all whom it may concern:

Be it known that I, WILLIAM ARTHUR RAMSAY, a subject of the King of Great Britain, residing at Honolulu, in the county 5 of Honolulu and Territory of Hawaii, have invented certain new and useful Improvements in Rotary Cane-Cutters, of which the following is a specification.

This invention relates to improvements in 10 rotary cane cutters such as are used for cutting the cane during its transit to the crushing mill into small lengths for the purpose of reducing its bulkiness and thereby facilitating its feed to the mill and the action of 15 the mill. These cutters usually consist of knives arranged in transverse series, spirally or otherwise and projecting radially from the rotating shaft upon which they are mounted. The rind of the cane upon which 20 the knives act is very hard; and the knives striking the hard rind of the crooked or irregularly disposed cane stalks with rapidly succeeding glancing blows are subject to more or less continuous lateral bending 25 stresses, with the result of frequent breakage, the fractures usually occurring through the holes for the fastenings by which the knives are secured in their holders and being more liable to occur as the dullness of the 30 knives, after a period of use, becomes more pronounced. Such breakage of the knives not only impairs the action of the cane cutter but develops a still greater disadvantage 35 in that the broken knives pass with the cane into the mills, greatly damaging the rollers and sometimes causing serious accidents.

The objects of the present invention are to 40 overcome the disadvantages above noted and to provide a cutter whose knives will efficiently perform their work yet which will not be liable to breakage from the causes noted.

With these objects in view the invention is 45 directed more particularly to the construction of the knife holders and the means of connection between said holders and the knives and proposes a construction wherein the knives will, as usual, normally occupy planes at right angles to the axis of rotation, yet will be free to yield in either direction in consequence of a glancing blow and in thus yielding will not be subject to 50 destructive lateral bending stresses.

Embodiments of the invention are illus-

trated in the accompanying drawings, 55 wherein:

Figure 1 is a side elevation, partly in section, of a unit consisting of a knife holder and a pair of knives carried thereby. Fig. 2 is an end elevation, partly in section, of the 60 same. Fig. 3, is a detail plan view of the blank from which the knife carrying jaw is fashioned. Fig. 4 is a partial plan view, and Fig. 5 is an end elevation showing the 65 rotary cutter as an entirety. Figs. 6 and 7 are detail sectional views in planes at right angles to one another showing a slight modification.

Similar characters of reference designate 70 corresponding parts throughout the several views.

The cutter is made up of a series of units 75 mounted on a common shaft 1, each unit consisting of a knife holder and the knife or knives 2 carried thereby. As shown, each knife holder carries two knives and consists of a sleeve 3 keyed on the shaft 1 and knife carrying jaws 4 connected to said sleeve.

According to the present invention, the 80 knives are mounted to swing laterally, i. e. to either side of their normal planes, within certain limits, and for this purpose they are preferably secured in the jaws 4 rigidly against lateral displacement relatively to 85 said jaws and the latter are pivotally mounted on the sleeves 3 for lateral swinging movement.

In the preferred embodiment of the invention the jaws 4 are each fashioned from the blank shown in Fig. 3 and consist of the 90 tubular bearing 5 and the ears 6 projecting therefrom in parallel planes and between which the shanks or heels of the knives 2 are secured by bolt or equivalent fastenings 7, the inner edges of said shanks or 95 heels terminating short of the central opening of the bearing 5, as shown in Fig. 1.

The pivotal connection between each jaw 4 and its sleeve 3 consists of a pivot pin or bolt 8 which passes through the bearing 100 5 and has its ends fitted in apertured lugs 9 projecting from the sleeve 3 and arranged adjacent each end of the bearing 5. A wear sleeve 10 preferably incases the pin or bolt 8 within the bearing 5. The pin 105 or bolt 8 and the bearing 5 extend transversely of the sleeve 3 and tangent to a circle whose radius extends from the axial

center of said sleeve to the longitudinal center of said bearing.

In order to limit the lateral swinging movement of the jaw 4, the sleeve 3 is provided with a stop lug 11 whose opposite sides are adapted to engage stop shoulders 12 formed with the bearing 5. These shoulders are preferably provided as the opposite points of an opening 13 which is punched or stamped at the center of the blank from which the jaw 4 is fashioned and which extends through a portion of the circumference of the bearing 5, the lug 11 projecting into this opening whose diameter is somewhat greater than the width of the engaging end of the said lug.

In the construction shown in Fig. 1, the shank or heel of the knife is secured in the jaw 4 by a plurality of fastenings 7 from which it follows that the knife is held rigid with said jaw against displacement in any direction.

The construction shown in Figs. 6 and 7 is similar to that shown in Fig. 1, except that instead of a plurality of fastenings 7, a single fastening 7^a is provided whose pin or shank forms a pivot about which the knife may be displaced in the direction of its plane. The pin or shank of the fastening 7^a is preferably incased in a wear sleeve 7^b; and the nuts or heads of said fastening are arranged to cause the ears 6 to exert frictional clamping pressure on the shank or heel of the knife in order that the knife may not be displaced in the direction of its plane, except upon the application of strong force. The special advantage of the construction shown in Figs. 6 and 7 is that it permits the knife to yield in the direction of its plane in case it encounters an obstruction carried over with the cane, such for example, as a car link or pin. In this way the knife, on striking an obstruction such as suggested, is protected against breakage.

The shaft 1 is driven either directly or by belt gearing from any suitable motor (not shown) and is rotated at from 200 to 600 R. P. M. The knives are maintained in normal planes at right angles to the axis of said shaft, and, after yielding laterally, are returned to such planes, by the centrifugal force incident to their rapid rotation as described. When the hard rind of the cane is struck a glancing blow, the knife freely yields laterally in either direction about the pivot of the jaw 4 and hence is not subject to any destructive lateral bending stresses which, in the cutters of ordinary construction, frequently produce breakage of the knives.

I claim:

1. In a rotary cane cutter, in combination, a shaft, a knife, and a knife holder mounted upon the shaft and having a pivot from which the knife projects radially of the

shaft as a center and about which the knife may swing laterally.

2. In a rotary cane cutter, in combination, a shaft, a knife, and a knife holder mounted upon the shaft and having a pivot from 70 which the knife projects radially of the shaft as a center and about which the knife may swing laterally and a second pivot about which the knife may swing in the direction of its plane. 75

3. In a rotary cane cutter, in combination, a knife, and a knife holder comprising a sleeve, a knife carrying jaw, and a pivot connection between the jaw and the sleeve arranged to permit lateral swinging movement of said jaw and knife. 80

4. In a rotary cane cutter, in combination, a knife, and a knife holder comprising a sleeve, a knife carrying jaw having a bearing and ears projecting from said bearing 85 and between which the knife is secured and a pivot pin carried by the sleeve and projecting through said bearing to permit lateral swinging movement of said jaw and knife. 90

5. In a rotary cane cutter, in combination, a knife, and a knife holder comprising a sleeve, a knife carrying jaw, a pivotal connection between the jaw and the sleeve arranged to permit lateral swinging movement 95 of said jaw and knife and a pivotal connection between the jaw and the knife arranged to permit swinging movement of the knife in the direction of its plane.

6. In a rotary cane cutter, in combination, 100 a knife, and a knife holder comprising a sleeve, a knife carrying jaw having a bearing and ears projecting from said bearing and between which the knife is held for pivotal movement in the direction of its plane 105 and a pivot pin carried by the sleeve and projecting through, said bearing to permit lateral swinging movement of said jaw and knife.

7. In a rotary cane cutter, in combination, 110 a knife, and a knife holder comprising a sleeve, a knife carrying jaw, a pivotal connection between the jaw and the sleeve arranged to permit lateral swinging movement 115 of said jaw and knife and co-acting parts on the sleeve and jaw for limiting said jaw in its swinging movement.

8. In a rotary cane cutter, in combination, 120 a knife, and a knife holder comprising a sleeve, a knife carrying jaw having a bearing provided with an opening in its outer circumferential face and ears projecting from said bearing and between which the knife is secured, a pivot pin carried by the sleeve and projecting through said bearing 125 to permit lateral swinging movement of said jaw and knife and a stop lug formed with said sleeve and projecting into said opening.

9. In a rotary cane cutter, in combination, 130 a rotatable shaft, a plurality of knives 135

projecting radially therefrom and a means of connection between said shaft and each knife to permit lateral swinging movement of the knife and to cause rotation thereof with said shaft.

10. In a rotary cane cutter, in combination, a rotatable shaft, a plurality of knives projecting radially therefrom, and a means of connection between said shaft and each 10 knife to permit lateral swinging movement

of the knife and also swinging movement thereof in the direction of its plane and to cause rotation of the knife with said shaft.

In testimony whereof I have hereunto set my hand in presence of two subscribing witnesses.

WILLIAM ARTHUR RAMSAY.
